DESIGN FOR A DESK STAND FOR PAPERS AND WRITING PARAPHERNALIA

Emanuel R. Posnack, Brooklyn, N. Y.

Application January 6, 1937, Serial No. 66,916

Term of patent 14 years

To all whom it may concern:

Be it known that I, Emanuel R. Posnack, a citizen of the United States, resident of Brooklyn, in the county of Kings and State of New York, have invented a new, original, and ornamental Design for Desk Stand for Papers and Writing Paraphernalia, of which the following is a specification, reference being had to the accompanying drawing, forming part thereof.

The figure is a perspective view of the desk stand for papers and writing paraphernalia showing my new design.

I claim:

The ornamental design for a desk stand for papers and writing paraphernalia substantially as shown.

EMANUEL R. POSNACK.
